[57] CLAIM

The ornamental design of a bathroom cabinet, as shown and described.

DESCRIPTION

FIG. 1 is a perspective view of the bathroom cabinet;
FIG. 2 is a right side elevational view of the bathroom cabinet, the left side elevational view being a mirror image of the right side elevational view;
FIG. 3 is a top plan view of the bathroom cabinet;
FIG. 4 is a front elevational view of the bathroom cabinet;
FIG. 5 is a rear elevational view of the bathroom cabinet; and
FIG. 6 is a bottom view of the bathroom cabinet.
The broken line representation of a knob is for illustrative purposes only and forms no part of the claimed design.
